WALL FLASHING

George E. Swenson, Hastings on Hudson, N. Y.,
assignor to The Celotex Corporation, Chicago,
Ill., a corporation of Delaware

Application July 25, 1938, Serial No. 221,054

4 Claims. (Cl. 72—127)

This invention relates to a wall construction wherein there is provided a wall flashing which is particularly adaptable for use as a through-wall flashing under coping and wherein the new and improved flashing hereof serves the purpose of both preventing the entry of water into the wall construction and as a resilient bedding for the coping.

The invention is illustrated in connection with the structure of a parapet wall wherein the improved flashing is illustrated as applied under the coping which, in previous and usual methods of wall construction, has been a portion of a building difficult to satisfactorily construct so that the entry of water into the wall structure at such portion thereof might be prevented.

In usual parapet wall construction or the like, it has customarily been the practice to merely bed the coping in mortar on the top of the brick or like wall structure and it happens that in many instances in such construction the coping is not firmly bedded on the top of the wall structure or the mortar bed therefore cracks or more or less disintegrates under the action of the elements so that water may be driven in under the coping by winds, where, after the water has once entered into the wall structure under coping it may find its way down through the parapet wall and into the interior of the building structure; or if such water eventually finds its way again to the exterior of the wall structure it usually carries various salts dissolved therein whereby as this water evaporates from the wall surface, the salts remain thereon as discoloring encrustations.

Even though in a construction such as is herein concerned the coping on a parapet wall may be properly bedded in mortar and this mortar line may remain intact, the entry of moisture into the wall in the manner as described may occur since there is apparently capillary phenomena involved which tends to carry any rain or the like on the under side of the coping and thus convey it into the wall beneath the coping where the undesirable effects as above mentioned will result.

It is an object of this invention to provide a parapet wall construction or like constructions involving window and door sills and the like wherein, there is provided in the wall construction elements which prevent the entry of water into the wall structure under the coping block or window or door sill or the like and wherein, in such construction there is utilized a structural element which is composed of such materials

and is fabricated in such manner that by the use thereof, utilized in accordance with teachings hereof, water is prevented from entering into a wall structure under the wall copings or under window or door sills and the like.

In addition to the objects of the invention just mentioned, it is a further object of the invention to provide what might be termed a coping flashing or the like which serves not only to prevent the entry of moisture into the wall under a coping or the like, but it is a further object of the invention to provide such a flashing composed of a material which is waterproof, which has a resilience so that slight inequalities 15 of the wall structure or of coping blocks or the like may be compensated for and still further, there is provided a substantially continuous water-proof barrier which has provision for the escape of water which may condense in the wall structure at or upon the surfaces of the flashing. Still other and further objects of the invention hereof will be apparent upon consideration of the following detailed description of the inventions hereof.

25 In the accompanying drawing, Figure 1 is a diagrammatic illustration of a portion of a wall structure illustrating a parapet wall having a coping thereon;

Figure 2 is a plan view of the coping flashing utilized in connection with the construction illustrated in Figure 1; and

Figure 3 is a cross-sectional view of the flashing element shown in Figure 2, the view being taken on line 3—3 of Figure 2.

35 In the various figures of the drawing, like numerals are employed to indicate like portions in the several figures.

In accordance with the construction illustrated there is indicated at 10 a portion of a wall construction, such as in usual building constructions, comprising an upward extension of a side wall to provide what is usually referred to as a parapet wall, that is, a wall extending up above the roof of the building to serve as a finish for 40 the side walls of a building and as a protection for the building roof deck and the roofing thereon which are diagrammatically indicated at 11. None of the details of the roof deck or roofing are indicated since the specific construction thereof is not involved in the inventions 45 herein disclosed.

In the construction illustrated, the parapet wall is indicated as of usual brick construction laid up with mortar but it is to be understood 50 that the specific disclosure is merely indicative

and that the parapet wall may be constructed of any usual building materials without affecting in any manner the application of the inventions hereof in connection with the parapet wall construction.

There is illustrated as laid on the top of the parapet wall 10 a through-wall flashing 12 which embodies my inventions, which through-wall flashing is bedded on the top of the parapet wall construction in a mortar bed 13 and on the upper surface of which through-wall flashing 12 there may be applied a further mortar bed in which is bedded a coping 14 which may be of any suitable coping material, as for example, the coping may be composed of stone or concrete or terra cotta or the like, the such coping materials being those generally used for the purpose.

The through-wall flashing 12 embodying the inventions hereof is of sheet form material, the base of which is felted fibrous substance, being sheets of such felted fibrous substances as are ordinarily manufactured and sold as fiber insulating board. The fiber insulating board base material is for the purposes hereof saturated with a water-proof material such as asphalt and as an example the such fiber board sheets may be saturated with asphalt to the extent of 100 to 200% of the weight of the fiber board with an asphalt of from 100 to 140 degrees F. melting point. The particular type of asphalt which falls within the limits of 100 to 140 degrees F. melting point need not be rigidly adhered to and there may be used for the saturation any asphalt or asphaltic material or equivalent saturants such as pitch or the like so long as the physical characteristics of the saturant are such that at the usual temperatures encountered the saturant is not unduly softened at the higher temperatures, so that it will run out of or bleed from the fiber board base material, or at the lower temperatures will not be so brittle that the saturated fiber board is fragile.

The saturated fiber board after saturation as described comprises the basic substance from which my through-wall flashing is produced and for the production of a through-wall flashing the saturated sheets of fiber board are prepared in suitable widths which are preferably the widths ordinarily encountered in the construction of building walls and of any convenient length. Preferably the saturated fiber sheet will be of about $\frac{1}{2}$ inch thickness but the such sheet may be of any reasonable thickness say from about $\frac{3}{4}$ inch to $\frac{3}{4}$ inch of thickness without in any manner departing from the inventions hereof. An average through-wall flashing strip in accordance with the inventions hereof may be approximately $\frac{1}{2}$ inch thick by 13 inches wide by, say, 4 feet in length.

The prepared base for the through-wall flashing material hereof will have formed in a surface thereof a series of channels or cut-outs indicated at 15 which channels or cut-outs as illustrated comprise a grid-like inter-connected pattern in which the individual channels extend from edge to edge, sideways of the sheet and wherein each such channel in its length crosses and connects with similar channels disposed at an angle 70 thereto.

It is to be understood that in forming the channel network on the surface of a through-wall flashing strip 12 as herein described that the channels 15 may be formed in the surface 75

of the strip 12 in any suitable manner, that is, the channels 15 may be impressed into the surface of the sheet 12 or they may be suitably cut in the surface of the sheet 12 or in some instances the desired channels may be formed in the surface of the sheet in the process of manufacture of the fibrous base sheet material. The described channels 15 are preferably provided on each of the opposite face surfaces of flashing sheets 12 but it is to be understood that the particular pattern of the channels provided in the surfaces of the sheet 12 is not at all critical and that the primary requirement therefore is that the channels shall either of themselves be continuous across the width of a sheet 12 or that through interconnection with other channels the channels 15 formed in the surface of sheet 12 shall connect with or extend to the edges of sheet 12.

20 In the formation of a wall structure embodying the inventions hereof, a brick wall or the like 10 is laid up in the customary manner and a prepared sheet of my through-wall flashing 12 is applied at the top of such brick wall structure 25 and is bedded thereon in a bed of mortar 13. In bedding the flashing strip 12 in the mortar bed 13, the mortar will enter into the channel pattern on the lower face, such channel pattern being indicated at 15a of the flashing strip 12 and due thereto the strip 12 will be firmly adhered at the top surface of the wall section 10 being anchored in place by the entry of the mortar into the channel pattern 15a as has been mentioned.

35 After the flashing strip 12 has been bedded on the top surface of the wall section 10, a further layer of suitable mortar may be applied on the top surface of strip 12 as indicated at 16 in which case the mortar will enter into the channel pattern 15 on the top surface of flashing strip 12 to securely anchor the such mortar layer with respect to the flashing strip 12. After mortar 16 has been applied to the top surface of flashing strip 12 the coping 14 may be applied and bedded 45 in the mortar layer 16.

50 In the construction of the flashing strip 12 the strip is preferably at its ends suitably scarfed or cut on a diagonal through the thickness thereof so that at the ends there are provided complementing diagonal surfaces 17, which surfaces 17, when similar flashing strips are laid up in a wall construction the scarfed ends 17 will overlap so that at the joints there is provided a seal rather than an open joint which would 55 result were the ends of the sheets merely cut square and butted when applied. Of course the ends 17 shown as scarfed or diagonally cut may be instead cut as ship-lap or tongue-in-groove joints or of other suitable interlocking or overlapping construction.

60 In a parapet wall constructed as above described and embodying the inventions hereof, it will be seen that when constructed in accordance herewith there is provided a such wall structure in which at the top thereof, under the coping, there is provided a continuous water-proof barrier extending through the width of the wall and along the length thereof. This water-proof barrier 12 provided under the coping 14 serves various functions in that the through-wall flashing prepared as has been hereinbefore described has a reasonable resilience so that it may give slightly to compensate for slight irregularities either in construction of wall 10 or in the manufacture of the coping 16. The flashing 12, is due to its

saturation as has been described, a water-proofed material and rain beaten in under the coping by wind will not enter into the flashing strip 12. Due to the resilience of the strip as has been mentioned which tends to the formation of a continuous and solid bond between the mortar beds 13 and 16 and the surfaces of the flashing strip 12 there are no voids into which moisture is liable to be driven by the wind and further, due to the secure bond which may be obtained, there is little or no tendency for moisture to travel into the wall along the faces of the flashing strip 12 under the influence of capillarity.

Should by any chance some moisture be driven into the wall structure under the coping 14 or should moisture pass through such coping at joints thereof, the penetration of such moisture into the wall proper will be prevented by the water-proof flashing strip 12 which forms that portion of the wall construction immediately under the coping course. Any moisture which may in some manner get under the coping course 14 will be intercepted at the surface of flashing strip 12 and may bleed or weep along channels 15 to the exterior edges of the wall structure which bleeding or weeping of such moisture along such channels even though they are substantially or completely filled with mortar will occur due to the fact that the mortar filling the channels 15 provides in effect capillary ducts which tend to convey any moisture from the interior of the wall structure to the exterior surface thereof.

In the preparation of the flashing strips 12, in addition to the saturation of the fiber board base material as has been described, it may in some instances be advantageous to surface coat the surfaces of the base material, after saturation thereof, with an asphaltic or more or less similar substance, which surface coating substances may be substantially the same as that which is used for the saturation of the fiber sheet, although, preferably the such surface coating will advantageously be of an asphalt or the like having a slightly lower melting point than that of the saturant.

When the flashing sheet 12 is provided with a surface coating as has been just described, the finished flashing sheet is more nearly completely water-proof than though such coating were not provided and such coating due to its physical characteristics affords a somewhat more secure bond between the faces of the flashing 12 and the mortar bed in which it is laid and which is laid thereon.

Whereas the above description of the invention hereof has been particularly directed to the provision of a through-wall flashing for use under the coping of a parapet wall, it is to be understood that the inventions hereof may be utilized in other relation in the construction of building walls and the like and it is comprehended that the flashing strip hereof shall be used not only in connection with the construction of parapet walls but that such may be utilized in any building walls wherein the provision of a through-wall flashing is advisable or desirable.

The through-wall flashing strips 12 as described will of course be made in any suitable

widths and lengths and thickness and it is to be understood that the strips may be initially formed to the desired size or that the flashing material may be prepared in large sheets and cut to size as required.

Variations and modifications of the materials hereof and the method of utilization thereof will be readily apparent to those skilled in the art to which the inventions hereof appertain and it is my intention that the such various apparent adaptations and variations of my invention shall be comprehended within the scope of this disclosure insofar as the same may be defined within the terminology of the appended claims.

15 The inventions hereof having been described in detail, I claim:

1. A resilient and waterproof flashing sheet comprising a sheet of asphalt saturated felted fiber board, a surface thereof having a plurality of diagonal intersecting channels extending across the board from edge to edge, each channel comprising a receptacle for mortar as well as a duct for conveying capillary seepage water from a wall in which the flashing sheet is incorporated.

2. A resilient and waterproof flashing sheet comprising a felted fibrous board having a waterproof coating over the surfaces thereof and the surfaces thereof having a plurality of diagonal intersecting channels extending across the board from edge to edge, each channel comprising a receptacle for mortar as well as a duct for conveying capillary seepage water from a wall in which the flashing sheet is incorporated.

3. As an article of manufacture, a resilient and waterproof flashing sheet adapted to be incorporated in a wall and comprising a board form felted fibrous sheet varying in thickness within the range of from substantially $\frac{1}{4}$ " to $\frac{3}{4}$ " and having a waterproof coating over the surfaces thereof, the board form sheet in addition saturated with a waterproofing, the saturant having in general physical properties of asphalt of from 110° F. to 180° F. melting point, the surfaces thereof having a plurality of diagonal intersecting channels extending across the board from edge to edge, each channel comprising a receptacle for mortar as well as a duct for conveying capillary seepage water from a wall in which the flashing sheet is incorporated.

4. As an article of manufacture, a resilient and waterproof flashing sheet adapted to be incorporated in a wall and comprising a board form felted fibrous sheet varying in thickness within the range of from substantially $\frac{1}{4}$ " to $\frac{3}{4}$ " and having a waterproof coating over the surfaces thereof, the board form sheet in addition saturated with a waterproofing, the saturant having in general physical properties of asphalt of from 110° F. to 180° F. melting point, the surfaces thereof having a plurality of diagonal intersecting channels extending across the board from edge to edge, each channel comprising a receptacle for mortar as well as a duct for conveying capillary seepage water from a wall in which the flashing sheet is incorporated, the sheet at its ends provided with complementally formed interfitting areas adapted to sealingly overlap similar complemental areas of adjoining sheets.

5. In a wall finishing construction wherein an upstanding wall is capped with a coping, a resilient and waterproofing barrier interposed between the underside of the coping and top of the wall, the said barrier comprising a waterproofed felted fiber board and having formed in the top and bottom faces thereof a plurality of diagonal intersecting channels extending across the board from edge to edge, each channel comprising a receptacle for mortar as well as a duct for conveying capillary seepage water from the wall in which the flashing sheet is incorporated, the said board bedded on top of the wall in mortar and the coping bedded on top of the board in mortar.

GEORGE E. SWENSON.
